UNITED STATES PATENT OFFICE.

GEORGE F. KONOLD, OF ASPINWALL, PENNSYLVANIA, ASSIGNOR TO IRON CITY TOOL WORKS, LIMITED, OF PITTSBURG, PENNSYLVANIA, A LIMITED COPARTNERSHIP UNDER THE LAWS OF PENNSYLVANIA.

METHOD OF MAKING MATTOCKS AND SIMILAR TOOLS.

No. 909,000.

Specification of Letters Patent.

Patented Jan. 5, 1909.

Application filed December 23, 1904. Serial No. 238,121.

To all whom it may concern:

Be it known that I, GEORGE F. KONOLD, a resident of Aspinwall, in the county of Allegheny and State of Pennsylvania, have invented a new and useful Improvement in Methods of Making Mattocks and Similar Tools; and I do hereby declare the following to be a full, clear, and exact description thereof.

10. My invention relates to the manufacture of mattocks, hoes, and similar tools, its object being to develop the same from a punched blank by successive pressing operations and in that way to provide for the shaping of the 15 blank and the rapid and cheap manufacture of the same of standard and uniform shapes.

To these ends the invention consists, generally stated, in making these mattocks or like tools from heated punched blanks by regular reciprocating pressing strokes the operations including the following steps: lengthening the blank and initially developing a central longitudinal rib; then spreading the blank close to the eye and fully developing 25 the eye by pressure applied close to the eye while supporting the eye internally, this operation also lengthening the blank and further developing the longitudinal rib; then further spreading each side of the blade and 30 tapering the same laterally by separate pressing operations with transversely inclined dies,—and by the same pressing strokes developing a longitudinally tapered face in the front or forward portion of the 35 blade; and further edge-pressing the blade and the curved shoulders at the junction of the eye by pressing strokes upon the edges of the blade which at the same time hold the blank from longitudinal movement by the 40 partial envelopment of the eye and finish the junction of the blade and eye, and maintain the eye central of the blade.

It also consists in certain steps in the manufacture of the mattocks included in the 45 above general manufacture, as hereinafter set forth and claimed.

To enable others skilled in the art to employ my invention I will describe the same more fully, referring to the accompanying 50 drawing, in which—

Figure 1 shows a press containing dies employed in the practice of the method; Fig. 2 shows perspective views of the top and bot-

tom dies for the first pressing stroke; Fig. 3 shows perspective views of the top and bottom dies used in fully developing the eye and spreading the blank; Fig. 4 is a longitudinal central section of the dies of Fig. 3; Fig. 5 is a perspective view of the bottom die used in developing the transverse inclines to the 55 blade and its incline or taper toward the cutting edge; Fig. 6 is a side view of the same illustrating its action upon the blank; Fig. 7 is a cross section on the line 7—7 Fig. 6; Fig. 8 is a perspective view of the dies used for 60 edging the tool and holding the eye to shape; and Figs. 9 to 13 are views illustrating the 65 different stages of the blank from the punched blank to the finished tool ready for trimming and grinding.

The press illustrated in Fig. 1 shows a press suitable for the practice of the invention, the main factor in connection with the press being that it provides for regular fixed pressing strokes developed by a regular reciprocating press having a stationary anvil die and a series of reciprocating die blocks operated at uniform strokes, as distinguished 70 from the ordinary hammer die strokes by which mattock blades have heretofore been 75 developed and in which the development of the article depends upon the eye of the workman rather than upon the fixed stroke of the die. In the said press the housings are shown at 1, these housings carrying the anvil 80 block 2 on which are supported the anvil dies, and having the horizontal eccentric shaft 3 carrying suitable eccentrics 4 with eccentric straps and pitman extensions 5, the reciprocating die block 6 moving in 85 guides 7, carrying the different top or reciprocating dies above referred to. The press may be driven by any suitable power. It is 90 illustrated as driven by a motor 8 through suitable gearing 9 95.

I will describe the different dies employed in connection with the work performed so that the regular development of the blank by the dies to the finished shape may be understood. The dies 11 12 are intended to 100 stretch the blank lengthwise and develop initially the central longitudinal rib. For this purpose the top face of the lower die 11 is slightly depressed toward its front end face, and is provided with a longitudinal recess 13 in its top face and a recess 14 in its

front end face, while the top die 12 is shown with a plain bottom face to press directly upon the top of the blank, spread it somewhat and cause its stretching or lengthening. 5 The original punched blank from which the mattock is developed is shown in Fig. 9, having the eye 15, the extension 16 from which the mattock is developed, and being illustrated as having on the other side thereof the 10 blank portion 17, which is subsequently hammered out to form the pick end or cutter of the tool. In the use of these dies the heated blank is placed upon the bottom die 11 with the end of its eye fitting up against 15 or into the recess 14 on the lower die, which serves to center the blank and upon the pressing stroke the upper die 12 strikes upon the blank, its tendency being to stretch the metal and so elongate the metal portion 16, 20 the die at the same time forcing the eye portion backward, pushing it away from the groove 14 and the resulting stroke forming a blank, as shown in Fig. 10, in which the metal has been spread somewhat, lengthened, and 25 the central longitudinal rib 10 initially developed. The blank may be given a second pressing stroke in these dies if desired, the effect of this stroke being indicated by dotted lines. It is then turned over and placed 30 upon the anvil die 18 illustrated in Figs. 3 and 4, which in connection with the upper pressing die 19 performs a peculiar and important function in the development of the blank, fully developing the eye and spreading 35 the blank close to the eye while also preferably elongating it and fully developing the central longitudinal rib. For this purpose the lower die is provided near its forward end with a horn or mandrel 20 projecting upwardly from its top face over 40 which the eye 15 of the blank fits, and by which it is supported against longitudinal movement under pressure of the upper die 19. This upper die 19 has, as shown, the 45 longitudinal recess 21 broad and deep at the front end and tapering and narrowing toward the rear end of the die, while extending upwardly along its front face or end and connected thereto by the curved inclined 50 faces 22 is the end recess 23, the end recess and the curved portions 22 being of such shape as to fully develop the eye, pressing down the metal of the blank to form the eye of proper depth, and also to spread the metal 55 close to the eye laterally upon the anvil die 18, their function being to so spread the metal of the blank while it is held against longitudinal movement by the horn or mandrel 20 as to force the metal out laterally at this 60 point and provide sufficient metal for forming the rounded shoulders close to the eye of the finished blank. At the same time the longitudinal recess 21 tapering toward the rear end of the die aids further in lengthening 65 the blank, drawing it out for practically the full length of the dies and providing a blank such as illustrated in Fig. 11, having the fully developed eye portion 24, rounded shoulders 25 with the fully developed longitudinal rib 26. These dies 18 and 19 thus 70 serve by the single pressing stroke to develop the main portion of the blank and bring it into condition for finishing. In the finishing of the blank the pressing dies illustrated in Figs. 5 to 7 when combined with the 75 edging dies illustrated in Fig. 8, serve to bring the blank shown in Fig. 11 to its final form. The heated blank which may meantime have been edged, is plated out to the desired width and shape of mattock blade, 80 principally by the dies of Figs. 5 to 7. In these dies the anvil die 27 is of peculiar shape, having the central rib 29 with the transverse inclined face 30 on each side of that rib, and extending down from this anvil face each front corner of the die is beveled off as at 31 to permit the blank to be so placed upon the anvil that the rounded shoulder 25 thereof may be placed upon the transversely inclined or tapered face 30 of 85 the die. The beveled end portion 31 and the transversely inclined portion 30 of the die are connected by the diagonal curved inclined portion 32 corresponding substantially to the side face of the finished 90 developed eye and rounded shoulder. The top die 28 is a simple plain faced die adapted to press the blank upon the peculiar inclined faces of the lower die. The inclined face portions of the mattock blade developed in 95 the dies of Figs. 3 and 4 can thus be spread out laterally by separate pressing operations on one or the other of said blade portions 33, the heated blank being first placed on one 100 side of the die to develop one blade portion 33, and then transferred to the other side of the die to develop the other blade portion as illustrated in dotted lines, the blade being thus spread out by one or more pressing strokes on each side, as considered necessary. 105 These dies 27 and 28 are also peculiar in another feature. Beyond each transverse inclined face 30 is the longitudinal inclined face 34 which is connected to the transverse inclined face 30 along the diagonal line 35 which unites with the rib portion 29 of the die. The inclined or tapered die faces 34 extend toward the rear end of the die block, and serve to form on the finished blank the longitudinal taper face 36, extending toward 110 the cutting edge. As the blanks are swaged on one or the other die face 30 to spread out the sides of the blank, by means of these longitudinal tapered faces 34 the forward end of the blank is so pressed into shape as to develop the natural taper face extending toward the cutting edge and spreading out the rounded corners 25 of the blade, bringing the blank substantially to the shape shown in 115 Fig. 12. The blank may be spread in this 120 125 130

way according to the desired length and thickness in the different parts of the mattock blade and the metal it contains.

During the pressing operations of the dies of Fig. 4 it is important to hold the edges of the mattock and its eye in proper shape and centrally of the finished mattock, and edge-finish the junction of the eye and blade, and so produce tools of uniform shape. For this purpose the dies of Fig. 8 are employed with the dies of Figs. 5 to 7, the top and bottom dies 38 of Fig. 8 being of practically the same shape, each having near the forward end the V-shaped projection 39 with the curved face 40 in front of the same, this curved face 40 corresponding in shape to the desired finished shape of the eye 24, while back of such V-shaped projection 39 is the curved face 41 corresponding to the desired curve of the shoulder portion 25 of the mattock blade, and beyond the same the inclined edging face 42 which flares apart according to the desired spread or increasing width of the finished mattock blade.

In the previous steps in the manufacture of mattocks there is liability of irregularity. For example, in the irregular spreading of the metal in the dies 18 and 19 of Figs. 3 and 4, or in the subsequent irregular spreading of the metal on each side of the central rib by the action of the dies 27 and 28 of Figs. 5 to 7, and it is important that the eye shall be held central of the mattock. These dies 38 therefore serve not only to give the desired finished shape to the blade portion of the mattock by holding the blank from longitudinal movement by the partial envelopment of the eye and at the same time forcing the metal forward after it has been spread by the dies of Figs. 5 to 7, but also hold the eye central of the blade, give finish to the shoulders of the blade, and finish the junction of the eye and blade. In the manufacture of the mattocks the blank can be subjected to the spreading stroke of the dies 27 and 28 and then edged by the dies 38, which will serve at the same time to elongate the blank, and by several such strokes of both dies the mattock can thus be brought to finished shape both of eye and mattock blade, as shown in Fig. 13. The mattock blade so formed can then be finished by shearing ready for subsequent grinding, and after the plating out of the cutter end 17 of the original blank it may be ground and finished in the ordinary way.

By my invention I am thus enabled by a series of regular reciprocating pressing strokes controlled and guided by the workman to rapidly and at a single heat develop from the rough punched blank a finished mattock blade of practically exact shape, so that the eye and mattock blade portion of each particular article are of standard shape and of better finished form than is possible

to be obtained by the ordinary work either of the hand or power hammer. This is made practicable by imparting to the dies the regular reciprocating strokes by which in the different manipulations of the blank at the will of the operator the different parts of the blank can be subjected to the exact pressure desired or required to develop the particular part of the blank instead of depending upon the heat and consequent ductility of the blank or the weight of the hammer blow, both of which are uncertain factors. And I am enabled to so develop the mattock blade and eye with few pressing strokes while properly controlling the flow of the metal both to form a finished eye, and blade with proper rounded corners close to the eye, transverse and longitudinal tapers, the operation being cheaper and better, and more perfectly finished tools being produced.

What I claim is:

1. The herein described method of forming mattocks and like tools from heated punched blanks by regular reciprocating pressing strokes, including the following steps: lengthening the blank and initially developing a central longitudinal rib, then spreading the blank close to the eye and developing the eye by pressure applied close thereto while supporting the eye internally, then further spreading each side of the blade close to the eye and tapering it laterally by separate pressing strokes with transversely inclined dies and by the same pressing strokes developing a longitudinally tapered face at the front or cutter portion of the blade, and then edge pressing the blade portions developing the junction of the blade and eye and maintaining the eye central of the blade by pressing strokes while holding the blank from longitudinal movement by dies partially enveloping the eye.

2. The herein described method of forming mattocks and like tools from heated punched blanks by regular reciprocating pressing strokes, consisting in lengthening the blank and initially developing a central longitudinal rib, then further developing the longitudinal rib and spreading the blank close to the eye and fully developing the eye by pressure applied close thereto while supporting the eye internally against longitudinal movement, and then further spreading each side of the blade close to the eye and tapering it laterally by separate pressing strokes with transversely inclined dies.

3. As steps in the manufacture of mattocks or like tools from heated punched blanks by regular reciprocating pressing strokes, spreading the blank close to the eye and fully developing the eye by pressure applied close thereto while supporting the eye internally against longitudinal movement, and then further spreading each side of the blade close to the eye and tapering the

same laterally by separate pressing strokes with transversely inclined dies.

4. As steps in the manufacture of mattocks or like tools from heated punched blanks by regular reciprocating pressing strokes, spreading each side of the blank close to the eye and tapering the same laterally by separate pressing strokes with transversely inclined dies.

10 5. As steps in the manufacture of mattocks or like tools from heated punched blanks by regular reciprocating pressing strokes, spreading each side of the blade and tapering the same laterally by separate

15 pressing strokes with transversely inclined dies, and by the same separate pressing strokes developing a longitudinally tapered face on the front or cutter portion of the blade.

20 6. As steps in the manufacture of mattocks or like tools from heated punched

blanks by regular reciprocating pressing strokes, spreading each side of the blade close to the eye and tapering the same laterally by separate pressing strokes with 25 transversely inclined dies, and then edge pressing the blade and the curved shoulders at the junction of the eye and blade and maintaining the eye central of the blade by an edge pressing stroke with dies partially 30 enveloping the eye and so holding the blank from longitudinal movement; and repeating said lateral spreading strokes and edging stroke to gradually draw out the blade laterally and longitudinally.

In testimony whereof, I the said GEORGE F. KONOLD have hereunto set my hand.

GEORGE F. KONOLD.
